Primary Examiner—Susan J. Lucas**Assistant Examiner—Cynthia E. Ramirez****Attorney, Agent, or Firm—Broadbent, Hulse, Pierce & Pate****[57]****CLAIM**

The ornamental design for an apparatus for cleaning, polishing, and/or buffing surfaces, as shown and described.

DESCRIPTION

FIG. 1 is a perspective view of an apparatus for cleaning, polishing, and/or buffing surfaces showing a first preferred embodiment of my new design;

FIG. 2 is a right side elevational view of the embodiment of FIG. 1;

FIG. 3 is a left side elevational view of the embodiment of FIG. 1;

FIG. 4 is a front elevational view of the embodiment of FIG. 1;

FIG. 5 is a rear elevational view of the embodiment of FIG. 1;

FIG. 6 is a top plan view of the embodiment of FIG. 1; and,

FIG. 7 is a bottom plan view of the embodiment of FIG. 1.
